CLAIM

The ornamental design for an accessory for vehicle heating and air conditioning systems, as shown and described.

DESCRIPTION

FIG. 1 is a perspective front view of the accessory for vehicle heating and air conditioning systems showing our new design;

FIG. 2 is a top view of the accessory for vehicle heating and air conditioning systems of FIG. 1;

FIG. 3 is a front elevation view of the accessory for vehicle heating and air conditioning systems of FIG. 1;

FIG. 4 is a right side elevation view of the accessory for vehicle heating and air conditioning systems of FIG. 1;

FIG. 5 is a left side elevation view of the accessory for vehicle heating and air conditioning systems of FIG. 1;

FIG. 6 is a bottom view of the accessory for vehicle heating and air conditioning systems of FIG. 1; and

FIG. 7 is a perspective rear view of the accessory for vehicle heating and air conditioning systems of FIG. 1; and,

FIG. 8 is a rear elevation view of the accessory for vehicle heating and air conditioning systems of FIG. 1.

In the drawings, the broken lines depict unclaimed subject matter only and form no part of the claimed design.

1 Claim, 2 Drawing Sheets
